UNITED STATES PATENT OFFICE.

LYMAN W. KING, OF PROVIDENCE, RHODE ISLAND, ASSIGNOR OF ONE-THIRD TO JAMES J. BAILEY, OF PROVIDENCE, RHODE ISLAND, AND ONE-THIRD TO WALTER B. KING, OF MILFORD, MASSACHUSETTS.

TOY.

No. 922,775.

Specification of Letters Patent.

Patented May 25, 1909.

Application filed March 5, 1909. Serial No. 481,386.

To all whom it may concern:

Be it known that I, LYMAN W. KING, a citizen of the United States, residing at Providence, in the county of Providence and 5 State of Rhode Island, have invented a new and useful Improvement in Toys, of which the following is a specification.

My invention relates to toys and more particularly to a rotary whistling toy in which 10 rotary motion is imparted by means of the twisting and untwisting of an arrangement of cords secured on opposite sides thereof, and held in the hands of the operator.

The object of the invention is to provide a 15 more simplified construction and assemblage of the parts of the device than heretofore, and at the same time to provide a mechanically stronger toy of this character, which will be enabled to withstand the rough usage to 20 which toys of this class are usually subjected by the juvenile element. I attain these objects in the manner as fully described in the following specification and as more particularly pointed out in the appended claims.

25 In the accompanying drawings in which like numerals refer to like parts, throughout the several views, Figure 1 is a view taken on the line 1—1 of Fig. 2. Fig. 2 is a plan view of one of the sides of the toy. Fig. 3 is a 30 plan view of the side containing the perforations, and Fig. 4 is a view showing the use and operation of the improved whistling toy.

In the embodiment illustrated two cup-shaped members 1 and 2 are formed by suitable machinery from flat metal disks, with out-turned peripheral portions 3 3 and flat central portions 4 4 so that they present substantial flattened hollow spherical segments.

40 As illustrated in Fig. 1 of the drawings the peripheral edge portions of the two members are secured in abutting relation, the type of union being herein shown as formed by bending the peripheral edge of member 1 over 45 onto the adjacent similar portion of member 2 in which relation it may be soldered, brazed or otherwise suitably secured.

As depicted in Fig. 3 of the drawings member 2 is formed with two series of openings 5 5 preferably arranged at diametrically opposite points adjacent the periphery of said member, the functions of these openings being to establish communication between the interior of the toy and surrounding atmosphere, whereby when rotary motion is

imparted to the toy a whistling sound will be given thereby.

For the purpose of securing the cords to the toy, there is a pair of holders employed, each being formed of a strand of wire 6, constituted of a straight body portion bent to form a pair of eyes 7, which are in spaced relation to each other, and are spaced from the respective ends of the body portion of the wire. Each part 4 of the members 1 and 2 is 60 formed with a slot 9, which is located at the center of each member and which is of a length slightly in excess of the distance between the eyes 7, and through which said eyes project so as to extend on the outer 65 sides of the members. By reference to the drawings it will be obvious that due to the engagement of the ends of the wire bodies with the inner faces of the members 1 and 2, outward movement of such bodies is prevented and since in use the pressure on these bodies is continually in an outward direction 70 it will be evident that they will be held securely in position. After the wire cord holders have been related to the members 1 and 75 2, as above described, they are secured rigidly thereto by means of solder as at 8 in the drawings. Since the solder is arranged to engage or seat on that portion of the wire body which is between the eyes 7, and to the 80 rear of the slot 9, it will be evident that only the eyes 7 are exposed and the wire bodies are securely held in position.

In practice a pair of endless cords 10 are employed, same being passed through the 90 eyes and held in the hands of the operator after which the toy body is given a rotary motion to twist or wind the cord as depicted in Fig. 4, whereupon the operator moves his hands successively toward and away from 95 each other to thereby rapidly revolve the toy body which causes the same to emit a whistling sound.

Having thus described my invention, I claim as new and desire to secure by Letters Patent:

1. A toy including a hollow body formed with a slot on each of its opposite sides, a pair of cord holders each composed of a body having a pair of spaced eyes which latter 105 project through said slot to extend on the outer side faces of the toy body, and a cord connected to each pair of eyes.

2. A toy including a hollow body formed with a slot on each of its opposite sides, a pair 110

of cord holders each composed of a single wire strand bent to form a pair of spaced eyes, said eyes being projected through said slots, the ends of said wire strand being engaged with the inner faces of the hollow body sides at points beyond the ends of the slots, and cords connected to the eyes.

3. A toy including a hollow body, having a slot in each of its opposite sides, a pair of cord holders each composed of a body having a pair of spaced eyes which latter extend through said slots, a cord connected to each pair of eyes, and solder which seats on that part of the cord holders which is exposed through said slots and which fills the unoccupied portions of said slots.

4. A toy including a hollow body having a slot in each of its opposite sides, a pair of

cord holders each composed of a wire strand, having a straight body portion bent to form a pair of spaced eyes disposed adjacent the ends of said wire body, said eyes extending through said slots, the ends of said wire body extending beyond the ends of the slots and engaging the inner faces of the hollow body sides, cords connected to the eyes, and solder which seats on said body of the wire and fills the unoccupied portions of said slots.

In testimony whereof I have signed my name to this specification in the presence of two subscribing witnesses.

LYMAN W. KING.
